BUCKLE

Filed March 13, 1929

INVENTOR

William E. Hatheway.

BY

Geo. D. Phillips ATTORNEY

UNITED STATES PATENT OFFICE

WILLIAM E. HATHEWAY, OF BRIDGEPORT, CONNECTICUT

BUCKLE

Application filed March 13, 1929. Serial No. 346,562.

My invention relates to an improvement in garment buckles of the rustless wire frame type on one part of which is journaled the conventional webbing clamping lever. The invention relates more particularly to the novel construction of the one piece wire frame and the novel manner of threading the webbing therethrough and firmly anchoring its free end to the frame.

In describing the invention in detail, reference will be had to the accompanying drawings wherein like characters of reference denote corresponding parts in the several views in which—

Figure 1 represents the initial shaping of the buckle frame preparatory to forming it into the complete article.

Figure 2 is a front elevation representing the second operation.

Figure 3 is a side view of Figure 2.

Figure 4 is a similar side view of the frame showing the initial entrance of the end of the webbing.

Figure 5 is a side elevation of the frame and webbing showing the manner of anchoring the webbing to the frame.

Figure 6 is a front elevation of the complete buckle, broken view of the webbing anchored thereto and a view of the clamping lever in open position.

Figure 7 is a rear elevation of Figure 6, and

Figure 8 is a side elevation showing the webbing in proper working condition and the lever closed.

The initial or first operation of the wire buckle frame, shown in Figure 1, is composed of an upper elongated section A, and a lower wedge shaped section B narrower in its wider part than the upper section, both sections joined by a U-shaped formation as follows:—

The upper section comprises the two complementary clamping lever supporting pins 1, the side bars 2, and the two part web-

bing supporting bars 3, forming a part of the U-shaped formations 4, 5. The wedge shaped portion of the frame comprises the bars 6 as a part of the U-shape feature, deflected side bars 7 terminating in the horizontal webbing clinch bar 8.

The second operation consists in bending or U-shaping the lower or wedge shape part of the frame to bring the clinch bar 8 in alignment with the open spaces 9, 10, Figure 2, intermediate of the upper and lower sections of the buckle frame, and also to form seats 11, 12, for the end 13 of the webbing 14, as shown in Figures 4, 6, and 7.

The wedge shaped section is then closed to bring the central part of the clinch bar 8 and the intermediate webbing, forcibly against the U-shaped ends 4, 5, Figure 6, and at the same time force the side portions 8^a of the clinch bar together with the portions 15 of the webbing to partly embrace said ends and thus interlock said webbing to the frame, to form a secure and unyielding anchorage for the end of the webbing.

The wedge shape formation of the lower section B of the frame is an essential feature in the present buckle construction. The object is to throw the inclined sides 7 and 7^a of the folded wedge out of alignment with each other, Figure 2, so that the overlapping portions, as 7^a, will be forced against the webbing cotemporary with parts 8^a of the clinch bar, and give a shearing pinch to the webbing between the sides 7 and 7^a to form an additional grip with the clinch bar when said bar firmly embraces the frame between the sections and hidden between the webbing in the assembled buckle.

The webbing is threaded into the buckle frame by first passing it rearwardly through the elongated opening 16 and over the bar sections 3, and its end anchored as before mentioned. The rest of the webbing is then carried down to form the conventional loop 17, Figure 8, and thence, from the front, 90

passed through the opening 16, when the clamping lever 18 is closed to bring its gripping finger 19 in usual manner forcibly against the webbing. The upper section of the frame, carrying the clamping lever has a forward inclination, see numeral 2, Figure 8, to facilitate the initial entrance of the webbing from the rear.

Having thus described my invention what I claim is:—

1. A single piece wire buckle frame shaped to form an upper elongated section, a clamping lever journaled on a part thereof, a wedge shaped lower and narrower section having outwardly deflected side bars and a lower clinch bar, said lower section being U-shaped to form a seat for the end of the webbing, said clinch bar and webbing brought into forcible contact with the frame between the sections and partially embrace the same to form a firm anchorage for the webbing.
2. A single piece wire buckle frame shaped to form an upper elongated section, a clamping lever journaled on a part thereof, a depending wedge shaped and narrower clamping section having outwardly deflected side bars and a clinch bar, said depending section being U-shaped to form a seat for the end of the webbing, said U-shaped section closed to bring the clinch bar and webbing into forcible and partial embracement of the frame between the sections, and also force said deflected side bars out of alignment with each other to give a shearing pinch against the webbing to serve as an additional webbing holding means.

In testimony whereof I affix my signature.
WILLIAM E. HATHEWAY.
